OUTBOARD MOTOR

Hermann P. Below, New Braunfels, Tex.

Application July 12, 1946, Serial No. 683,091

3 Claims. (Cl. 115—18)

1

My invention relates to improvements in compressed air driven outboard motors for boats, and the primary object of my invention is to provide a portable device of this character which can be readily installed as a unit in a boat, and which produces its own compressed air for its operation as needed without recourse to an external source thereof, and in which the propelling component is provided with a water screw and a rudder which are together swingable by the operator of the boat to direct the boat in a straight ahead course or in a turn to either side.

Other important objects and advantages of my invention will be apparent from the following description and the accompanying drawings, wherein merely for illustrative purposes, a preferred embodiment of my invention is set forth in detail.

In the drawings:

Figure 1 is a fragmentary vertical longitudinal section taken through a boat and showing in side elevation a device according to my invention installed thereon.

Figure 2 is a top plan view of Figure 1.

Figure 3 is an enlarged fragmentary horizontal section taken through the air control valve, taken on the line 3—3 of Figure 1.

Figure 4 is a transverse vertical section on an enlarged scale, taken through Figure 1 on the line 4—4, and

Figure 5 is a fragmentary transverse section on an enlarged scale, taken on the line 5—5 of Figure 1.

Referring in detail to the drawings, the numeral 6 generally designates a boat, of which the bottom 7, sides 8, and stern 9 are shown. In accordance with my invention I locate on the bottom 7 or at some other suitable place a compressor component comprising a suitable motor 10 driving an air compressor 11, with a suitable flexible airhose 12 leading along the boat bottom 7 toward the stern 9, where said hose is connected in input relation to one end of a compressed air storage tank 12'.

The tank 12' may conveniently be cylindrical in form and be arranged crosswise and on brackets 13, on the bottom 7 immediately in front of the stern 9. A pressure gauge 14 may be provided on the same end of the tank 12' as the compressor input connection 15. The compressor component is designed to be operated to produce compressed air in the tank 12' for operation of the propelling component, whenever a drop below the required operating pressure is shown by the gauge 14.

The propelling component comprises a suitable

outboard motor clamp bracket 16, here shown as U-shaped to embrace upper part of the boat stern 9, and having a rearwardly extending arm 17, containing a thrust roller bearing 18, turnably mounting the tubular shaft 19, which is bent above the arm 17 at 20 into a forward extension 21, terminating at its forward end in a down-turned portion 22, which has a union 23 connecting with the upper end of a slack flexible airhose 24, which in turn is connected by a union 25 to the top of the tank 12' to receive compressed air therefrom.

A steering handle 26 extending forwardly from the tubular forward extension 21 is provided for 15 swinging the propelling component from side to side in the bearing 18 for steering the boat. Within convenient reach of the steering handle 26 is the normally forwardly extending, but laterally movable handle 27 of the air control valve 20 28 provided for controlling the passage of compressed air from the tank 12' through the tubular shaft so as to control the speed of operation of the propelling component, and hence the speed of the boat 6.

25 The air control or speed control valve 28 is incorporated in the tubular extension 21 and may consist of a casing 29 having an inverted conical chamber 30 in which turns an inverted frustro-conical hollow core 31 turnable by the handle 27, the core being provided with circumferentially spaced ports 32, 33 and 34, for example, of progressively greater length, and so spaced that the core can be turned so that none of them, or any one or two or all of them are closed by the sides 30 of the chamber 30 or exposed thereby, so that the valve may be either shut off or opened in gradients for lowest speed operation or full speed operation of the propelling component.

40 The propelling component further comprises the streamlined air turbine housing 35 secured to the lower end of the tubular shaft 19, with the latter opening into the rotor chamber 36 to jet air against the turbine wheel or rotor 37 therein, which includes the rearwardly extending shaft 38, journaled in the housing 35, and having secured on its rear end the safety type screw propeller 39.

45 A crescent shape rudder 40 depends from the housing 35 and above the housing the tubular shaft 19 supports a streamlined water foil 41.

The turbine chamber 36 has connected thereto an air exhaust pipe 42 which rises around the water foil 41 and up along the tubular shaft 19, around which it is turned, to terminate in a

downwardly and rearwardly directed tail pipe 43 above the foil 41.

It will appear from the foregoing that the propelling component may be operated like a modern gasoline or electric outboard motor, and may be detached from the boat and carried away for storage or other purposes, simply by loosening the clamp 16 and the connection with the flexible air hose 24, leaving in the boat only the compressor component and the tank 12'.

What is claimed is:

1. An outboard motor for mounting on the stern of a boat, comprising a clamp bracket adapted to be secured on the boat stern and having a vertical axis bearing, arranged to extend rearwardly beyond the stern, a rigid vertical tube having an upper portion thereof supportably journalled in said bearing, a turbine housing fixed on the lower end of said tube, said housing comprising a turbine chamber, a turbine rotor therein having a shaft extending rearwardly from said housing and equipped with a propeller, the said lower end of said tube communicating with the interior of said chamber in jetting relation to said turbine rotor whereby fluid moving downwardly through said tube and impinging upon said turbine rotor turns said rotor and drives said propeller, said upper part of said tube terminating above said bearing in a horizontal tubular extension projecting forwardly and serving as a tiller and as a conduit for conveying fluid under pressure to said vertical tube from a source on the boat.

2. An outboard motor for mounting on the stern of a boat, comprising a clamp bracket adapted to be secured on the boat stern and having a vertical axis bearing, arranged to extend rearwardly beyond the stern, a rigid vertical tube having an upper portion thereof supportably journalled in said bearing, a turbine housing fixed on the lower end of said tube, said housing comprising a turbine chamber, a turbine rotor therein having a shaft extending rearwardly from said housing and equipped with a propeller, the said lower end of said tube communicating with the interior of said chamber in jetting relation to said turbine rotor whereby fluid moving downwardly through said tube and impinging upon said turbine rotor turns said rotor and drives said propeller, said upper part of said tube terminating above said bearing in a horizontal tubular extension projecting forwardly and serving as a tiller and as a conduit for conveying fluid under pressure to said vertical tube

from a source on the boat, a fluid exhaust conduit leading from said chamber providing for escape of fluid under pressure from said chamber after impingement upon said turbine rotor, said exhaust conduit having a discharge end directed rearwardly so as to aid propulsion of the boat during operation of said propeller.

3. An outboard motor for mounting on the stern of a boat, comprising a clamp bracket adapted to be secured on the boat stern and having a vertical axis bearing, arranged to extend rearwardly beyond the stern, a rigid vertical tube having an upper portion thereof supportably journalled in said bearing, a turbine housing fixed on the lower end of said tube, said housing comprising a turbine chamber, a turbine rotor therein having a shaft extending rearwardly from said housing and equipped with a propeller, the said lower end of said tube communicating with the interior of said chamber in jetting relation to said turbine rotor whereby fluid moving downwardly through said tube and impinging upon said turbine rotor turns said rotor and drives said propeller, said upper part of said tube terminating above said bearing in a horizontal tubular extension projecting forwardly and serving as a tiller and as a conduit for conveying fluid under pressure to said vertical tube from a source on the boat, said turbine housing having a depending water foil positioned in the vertical plane of said propeller shaft so as to serve as a rudder for holding the boat on a straight forward course with said tiller in a straight forward position or for steering the boat when said tiller is swung to either side in conjunction with said propeller while in operation.
